ONE REVOLUTION HIGH-SPEED CYLINDER
PRINTING PRESSArtur Buttner, Heidelberg, Germany, assignor to
Schnellpressenfabrik A.-G. Heidelberg, Heidelberg,
Germany, a corporation of GermanyApplication March 22, 1950, Serial No. 151,272
In Great Britain January 9, 1950

6 Claims. (Cl. 101—173)

1

For two-color printing in one operation on one-revolution high speed cylinder presses, it is known to provide the printing cylinder with two printing or make-ready surfaces, each printing surface being associated with a special printing mechanism, namely a flat forme printing mechanism and a round forme print mechanism. A transfer cylinder associated with the printing cylinder and situated between the two printing mechanisms effects the transfer of the sheet to be printed after the first printing operation to the printing surface associated with the second printing mechanism.

In machines of this kind, the sheet feeding device is arranged above the round forme print mechanism, so that the latter is accessible only with difficulty. This arrangement also means that the feed device is in front of the flat forme printing mechanism. Consequently, in these machines, the round forme printing mechanism can function only as second printing mechanism, whereby the course of the working operations on this machine is fixed in a definite and positive manner.

The invention relates to a new construction of these one-revolution high-speed cylinder presses for two-color printing in one operation, whereby the possibility is provided of allowing the two printing mechanisms to operate in any desired sequence, of working with only one of the two printing mechanisms or of using the flat forme printing mechanism as embossing or stamping mechanism while printing with the round forme printing mechanism.

According to the invention, in a one-revolution high-speed cylinder printing press of the aforesaid type, the feed device is arranged in front of the round forme printing mechanism. This construction, in the first place, provides free accessibility of the round forme printing mechanism which is no longer covered by the feed device. The supervision of the machine, attendance of the inking mechanism for the round forme printing mechanism and in particular convenient mounting and adjustment of the formes on the cylinder are thereby considerably simplified. If the round forme printing mechanism is disconnected, the machine may be used for single color printing on the flat forme printing mechanism. The round forme printing mechanism may also be used alone, in which case the sheet to be printed is taken over by the grippers of the sheet distributor immediately after printing. If the round forme printing mechanism alone is used, the movement of the flat forme bed may be stopped, so that the machine then operates as

2

a sheet-printing rotary machine. If the transfer cylinder is arranged in front of the flat forme printing mechanism then, in the case of two-color printing, the round forme printing mechanism may operate first and then the flat forme printing mechanism, in which case the latter may be constructed as a stamping, embossing or perforating mechanism. In this construction also, the round forme printing mechanism may be used alone with delivery of the sheet immediately after printing.

Through the association of the various working members with the printing cylinder, in particular, however, the arrangement of the feed device in front of the round forme printing mechanism, a single-purpose machine with restricted course of working operations becomes a multi-purpose machine, in which the course of the working operations may be adjusted in a manner most suited to the occasion. If desired, the round forme printing mechanism may be followed by another round forme printing mechanism for a third color, operating on the same printing surface as the other printing mechanism. For the printer, this affords the possibility of printing off the round forme printing mechanism, at the first or second station, an advantageous adaptability according to the kind of printing work. This machine may thus be used in the same way for single color printing as for two and three color printing and as perforating or stamping machine with or without printing operation.

For a better understanding of the invention and to show how the same may be carried into effect, reference will now be made to the accompanying drawings, in which:

Figure 1 shows in diagrammatic cross-section a construction with a round forme and flat forme printing mechanism and

Figure 2 shows, likewise, in diagrammatic cross-section, a construction with two round forme printing mechanisms and one flat forme printing mechanism.

The printing cylinder 1, rotating in the direction of the arrow A and performing a printing operation on each revolution, has two printing surfaces 2, 3, each with its gripper system 4, 5, which are opened and closed in known manner by means not shown, and which seize the sheets for printing by their front edges. Clamping spindles 6, 7 are associated on the printing cylinder with each printing surface for tightening the dressing (packing), which also contains the necessary make ready, over the printing surfaces 2, 3.

Under the printing cylinder 1, a forme bed 9

3

is movable tangentially to the printing cylinder by means of roller guides 10 on a track 11 on the machine under-frame. The bed 9 carries the flat forme 8 which co-operates with the printing surface 2 when the bed 9 runs in the direction of the arrow B. Associated with the flat forme 8 is an inking mechanism 12.

Above the printing cylinder 1, a round forme cylinder 13 with inking mechanism 14 is mounted in the machine frame and rotates continuously, being controlled by known means, not shown, in such a manner that, on passing the printing surface 3 of the printing cylinder, it is lowered upon the latter and hence prints on said printing surface. The diameter of the round forme cylinder 13 is about one half or one third of the diameter of the printing cylinder 1.

Feeding of the sheets to be printed to the printing cylinder 1 is effected by means of a feed table 18 with feed mark 19, said table being arranged in front of the round forme cylinder 13 in the direction of rotation of the printing cylinder 1. At said mark 19, the straightened sheet is seized by the fore-gripper 16 mounted on a swinging lever 15, and through the swinging of the lever 15 about the spindle 17, it is delivered to the grippers 4 or 5 of the printing cylinder 1. The drive of the swinging lever 15 is reversible in such a manner that it delivers the sheets to the grippers 4 or 5 according to choice, and the control of the lifting mechanism for the round forme cylinder 13 is also adjustable, so that the latter may cooperate, according to choice, with the printing surface 2 or the printing surface 3.

Below the feed table or board 18, a transfer cylinder 22 is mounted on a shaft 21, its diameter amounting to half the diameter of the printing cylinder 1. The transfer cylinder 22 is provided with grippers 20 and is covered by a guard 23. The drive of the transfer cylinder 22 is so adjusted that its grippers 20 seize the sheet carried on the printing surface 2 by the grippers 4 of the printing cylinder 1, take it with them for one revolution and then deliver it to the grippers 5 associated with the printing surface 3. Each time they pass the feed table 18, the grippers 4 are therefore able to take the sheet from the fore-grippers 16.

Following the round forme cylinder 13 in the direction of rotation of the printing cylinder 1 is a gripper system 24 carried by endless chains 25. The chains 25 pass over sprocket wheels 26 carried on spindles 27. Here again the drive is reversible in such a manner that the grippers 24 can take the printed sheets from the grippers 4 or 5 of the printing cylinder 1 according to choice. The grippers 24 then convey the printed sheets with the printed side uppermost to the delivery stack.

With the arrangement described in the foregoing, it is possible to carry out the following printing work, always in one operation:

1. *Two-color printing, flat forme as first color, round forme as second color*

In this operation, the various working members of the machine are adjusted so that the fore-grippers 16 deliver the sheet to be printed to the grippers 4, the transfer grippers 20 take the sheet from the grippers 4 and deliver it to the grippers 5 of printing surface 3, from which it is then removed by the chain grippers 24. The round forme cylinder 13 is lowered on to the printing surface 3 while the latter is moving past it.

4

The sheet to be printed is thus carried by the grippers 4 on the printing surface 2 and is provided with a color impression upon the surface 2 rolling off on the flat forme printing mechanism 8. After this printing operation, the transfer grippers 20 take the sheet off and transfer it to the grippers 5 of the printing surface 3. On this printing surface 3 it now runs under the round forme cylinder 13 which is lowered for printing the second color and is then taken off by the grippers 24. The impression of each printing forme is thus effected on separate printing surfaces, as is required in multi-color auto-type printing, where the colors are one above the other for quality printing. Each forme can be made ready on the associated printing surface in known manner familiar to any book printer, using normal blocks for the round and flat formes.

20 2. *One-color printing by the flat forme*

The adjustment of the working members remains the same as for Example 1, but the drive of the round forme cylinder 13 is disconnected, so that the latter remains in the position lifted off the printing cylinder 1.

25 3. *One-color printing by the round forme*

30 In this method of printing, the adjustment of the working members may be retained as described for Example 1. The flat forme bed 8, however, remains empty or is disconnected.

35 Preferably, however, the drive of the round forme cylinder 13 is reversed in such a manner that it is lowered on passing the printing surface 2 and prints, the grippers 4 by reversal of the control dogs being then opened already on passing the take-off device, so that, therefore, the sheet to be printed remains on the printing cylinder only during the path of the grippers 4 from the feed table to the take-off device.

40 It is, however, also possible to allow the round forme cylinder 13 to cooperate with the printing surface 3, in which case the fore-grippers 16 are so controlled that they deliver the sheet to be printed to the grippers 5 of the printing surface 3.

45 4. *Two-color printing, round forme as first color and flat forme as second color*

50 The adjustment of the machine is such that the sheet is fed to the grippers 4 of the printing surface 2 and the round forme cylinder 13 works on the printing surface 2, on which the flat forme 8 is then printed off. The double printed sheet is then taken from the surface 2 by the transfer grippers 20 and delivered to the surface 3. On the passage of said surface 3 under the round forme cylinder 13, the latter remains in the raised position. Thus, both colors are printed off on printing surface 2 as may be advantageously used for display work, in which the colors lie side by side. In this case, the printing surface 3 is not used for printing but only for carrying the sheet out.

55 In the construction according to Figure 2, the transfer cylinder 22 is situated in front of the flat forme printing mechanism 8, 9 in the direction of rotation of the printing cylinder 1, while the inking mechanism 12 for this printing forme lies below the feed device 18. A second round forme cylinder 28 with inking mechanism 29 is arranged after the round forme cylinder 13.

60 The following printing work can be done with 75 this construction.

1. Printing in one color by one round forme

The fed and straightened sheet is delivered by the fore-grippers 16 to the gripper system 5 of printing surface 3. The round forme cylinder 13 is lowered into the printing position and prints off when the sheet passes thereunder. The round forme printing mechanism 28, on the contrary, is in the raised position and does not come into contact with the sheet. The one-color printed sheet is immediately taken off by the gripper system 24 and conveyed to the distribution stack. The flat forme bed 8, however, remains empty or is disconnected.

2. Printing in two colors by two round formes

Sheet lay and transfer is again effected by gripper system 5, and on passing the round formes 13 and 28, both formes print off successively. Removal of the sheet is then effected immediately again by distributor grippers 24. The flat forme bed 8, however, remains empty or is disconnected.

3. Printing in one color by the flat forme 8

The sheet is again delivered by fore-grippers 16 to the gripper system 5. The round forme cylinders 13 and 28 are stopped. The as yet unprinted sheet is taken by the gripper system 20 from the gripper system 5, carried round once and transferred to the following gripper system 4 of the printing cylinder 1. Printing off of the sheet on the flat forme 8 then takes place. The sheet is carried round further by the cylinder until it is conveyed by the gripper system 24 to the distribution stack. The gripper system 5, during further revolution, takes over the next unprinted sheet.

4. Three-color printing in which the round formes print first

Printing of the two round formes 13 and 28 against the printing surface 3, then sheet transfer to the gripper system 4 of the printing surface 2 and printing off thereof on the flat forme 8 as third color. The sheet is then carried out by the grippers 24.

5. Three-color printing in which the flat forme prints first

The unprinted sheets are, as before, transferred to the gripper system 5. On the first passage, however, the round forme cylinders 13 and 28 are in the raised position and do not print the sheet. As described before, the sheet is transferred by the gripper system 20 to the gripper system 4 of the printing cylinder 1. As the sheet lies on the printing surface 2, the flat forme 8 prints the first color off on the sheet. The round forme cylinders 13 and 28 then print off against this same printing surface, having now been lowered into the printing position. Thus, in this case, all three colors are printed off successively on the one printing surface 2. This possibility of printing offers considerable advantages in the printing of display work with colors situated side by side. The sheet is then removed by grippers 24 without the surface printed in three colors coming into contact with any part of the machine.

6. Stamping without printing

Instead of the dressing, the printing surface 2 is covered with a steel sheet of the thickness of the dressing or packing, and the flat printing forme 8 is replaced by a stamping forme. The round forme cylinders are stopped. Transfer

from the fore-grippers 16 takes place to the gripper system 5. The sheet passes the round forme cylinders 13 and 28 without printing. Grippers 20 then carry the sheet round to the gripper system 4, and stamping, grooving or perforating work is effected on the printing surface 2, over which is clamped a steel sheet, by the stamping, grooving or perforating tools carried by the flat forme bed 8. These are enclosed in frames in known manner. The stamped sheet is then carried round further until it is removed and carried out by grippers 24. The transfer cylinder 20, 21 and 22 is therefore arranged in front of the flat forme 8, so that transfer takes place before stamping, in order to prevent breaking off of the stamped material.

7. One or two color printing by the round forme and stamping, grooving, perforating or embossing in one working operation.

The sheet is again transferred to the gripper system 5. Printing off takes place by the round forme 13 as first color, followed in the case of two-color printing by the round forme 28 as second color, against printing surface 3. The printed sheet is then transferred by the gripper system 20 to gripper system 4. The sheet now lies on printing surface 2, over which is clamped a steel sheet. Stamping, grooving, perforating and/or embossing then takes place. The printed and, for example, stamped sheet is carried round further by printing cylinder 1 until it is taken off by grippers 24 and conveyed to the distribution stack. The round forme cylinders are raised when the printing surface 2 with the printed and stamped sheet passes them.

It is known in high-speed cylinder presses to raise the printing cylinder and to lower it during the printing operation. These known devices have not been shown for the sake of clarity. Likewise, the known means for opening and closing the various gripper systems have not been shown.

The stopping of the round forme cylinders is effected by drawing an index bolt in the driving wheel. Variation of the times of raising and lowering the round forme cylinders is likewise effected in known manner by shifting through 180° the driving eccentric for rotation of the printing cylinder 1.

With a construction of the machines according to the present invention, the printer is provided for the first time with the possibility either of printing off each color on a separate printing surface, as is required absolutely in multi-color auto-type printing for special quality work, since each color can be made ready independently, or for carrying out display work with colors side by side, the printing off by round forme and flat forme may take place in common on the printing surface for the flat forme. This latter possibility offers the printer further advantages in corresponding printing work in a more rapid make-ready of the machine, because in this case, it is only necessary to make ready on one printing surface of the cylinder 1, or if he is working only from the round forme or formes, he can use the machine for sheet rotary printing by disconnecting the flat forme bed movement.

I claim:

1. A one revolution high-speed cylinder press including, an annular printing cylinder, a flat form printing mechanism, a round form printing mechanism, a separate printing surface on the printing cylinder for each of said printing mechanisms, a transfer cylinder for transferring

the sheet to be printed upon during one revolution of the printing cylinder from one of its printing surfaces to the other printing surface, a sheet feeding device, and a sheet removing device, the round form printing mechanism being situated between the sheet feeding device and the sheet removing device and the round form printing mechanism being adjustable for printing on the printing surface of the flat form printing mechanism.

2. High-speed press according to claim 1, wherein the sheet feeding device is situated between the transfer cylinder and the round form printing mechanism which is disposed behind the said transfer cylinder in the direction of rotation of the printing cylinder.

3. High-speed press according to claim 1, wherein a second round form printing mechanism is arranged behind the first round form printing mechanism in the direction of rotation of the printing cylinder both round form printing mechanisms being situated between the sheet feeding device and the sheet removing device.

4. High-speed press according to claim 1, wherein the transfer cylinder is arranged in front of the flat form printing mechanism in the direction of rotation of the printing cylinder.

5. A one revolution high-speed cylinder press, including, in combination, an annular printing cylinder having opposite arcuate peripheral printing surfaces, sheet gripping means at the leading edge of each of said printing surfaces, a flat form beneath the cylinder and movable tangentially relative thereto, a round form mounted

above the printing cylinder to be moved into and out of contact therewith, sheet feeding means arranged between the flat form bed and the round form cylinder to feed sheets in the direction of rotation of the printing cylinder, a sheet transfer cylinder having its axis mounted below the axis of the printing cylinder and rotatable in a direction opposite to that of the cylinder, means for inking the flat form and the round form, and sheet discharge means located above the axis of the printing cylinder and on the side thereof opposite the sheet feeding means, the round form being situated between the sheet feeding means and sheet discharge means.

15 6. The combination according to claim 5, wherein two round form cylinders both situated between the sheet feeding means and sheet discharge means are provided at the upper side of the printing cylinder, and the sheet transfer cylinder is mounted beneath the sheet discharge means.

ARTUR BUTTNER.
